(57) CLAIM

The ornamental design for a holster device as shown and described.

DESCRIPTION

FIG. 1 is a top, front, right-side perspective view of a holster device in a lid-closed configuration, according to a new design.

FIG. 2 is a bottom, rear, left-side perspective view of the holster device of FIG. 1.

FIG. 3 is a top, front, left-side perspective view of the holster device of FIG. 1.

FIG. 4 is a bottom, rear, right-side perspective view of the holster device of FIG. 1.

FIG. 5 is a top, rear, left-side perspective view of the holster device of FIG. 1.

FIG. 6 is a bottom, front, right-side perspective view of the holster device of FIG. 1.

FIG. 7 is a top, rear, right-side perspective view of the holster device of FIG. 1.

FIG. 8 is a bottom, front, left-side perspective view of the holster device of FIG. 1.

FIG. 9 is a front elevation view of the holster device of FIG. 1.

FIG. 10 is a rear elevation view of the holster device of FIG. 1.

FIG. 11 is a right-side elevation view of the holster device of FIG. 1.

FIG. 12 is a left-side elevation view of the holster device of FIG. 1.

FIG. 13 is a top view of the holster device of FIG. 1.

FIG. 14 is a bottom view of the holster device of FIG. 1.

FIG. 15 is a bottom, rear, right-side perspective view of the holster device of FIG. 1.

FIG. 16 is a bottom, rear, left-side perspective view of the holster device of FIG. 1.

FIG. 17 is a bottom, front, left-side perspective view of the holster device of FIG. 1.

FIG. 18 is a bottom, front, right-side perspective view of the holster device of FIG. 1.

FIG. 19 is a top, front, right-side perspective view of the holster device of FIG. 1 in a lid-open configuration including a containment apparatus located in an inner conduit of the holster device, the containment apparatus having an empty central conduit.

FIG. 20 is a bottom, rear, left-side perspective view of the holster device of FIG. 19.

FIG. 21 is a top, front, left-side perspective view of the holster device of FIG. 19.

FIG. 22 is a bottom, rear, right-side perspective view of the holster device of FIG. 19.

FIG. 23 is a top, rear, left-side perspective view of the holster device of FIG. 19.

FIG. 24 is a bottom, front, right-side perspective view of the holster device of FIG. 19.

FIG. 25 is a top, rear, right-side perspective view of the holster device of FIG. 19.

19.

FIG. 26 is a bottom, front, left-side perspective view of the holster device of FIG. 19.

FIG. 27 is a front elevation view of the holster device of FIG. 19.

FIG. 28 is a rear elevation view of the holster device of FIG. 19.

FIG. 29 is a right-side elevation view of the holster device of FIG. 19.

FIG. 30 is a left-side elevation view of the holster device of FIG. 19.

FIG. 31 is a top view of the holster device of FIG. 19.

FIG. 32 is a bottom view of the holster device of FIG. 19.

FIG. 33 is a top, front, right-side perspective view of the holster device of FIG. 19.

FIG. 34 is a top, rear, left-side perspective view of the holster device of FIG. 19.

FIG. 35 is a top, front, left-side perspective view of the holster device of FIG. 19.

FIG. 36 is a top, rear, right-side perspective view of the holster device of FIG. 19.

FIG. 37 is a bottom, rear, right-side perspective view of the holster device of FIG. 19.

FIG. 38 is a bottom, rear, left-side perspective view of the holster device of FIG. 19.

FIG. 39 is a bottom, front, left-side perspective view of the holster device of FIG. 19.

FIG. 40 is a bottom, front, right-side perspective view of the holster device of FIG. 19.

FIG. 41 is a top, front, right-side perspective view of the holster device of FIG. 1 in a lid-open configuration including a containment apparatus located in an inner conduit of the holster device, the containment apparatus including a second adaptor device in a central conduit of the containment apparatus.

FIG. 42 is a bottom, rear, left-side perspective view of the holster device of FIG. 41.

FIG. 43 is a top, front, left-side perspective view of the holster device of FIG. 41.

FIG. 44 is a bottom, rear, right-side perspective view of the holster device of FIG. 41.

FIG. 45 is a top, rear, left-side perspective view of the holster device of FIG. 41.

FIG. 46 is a bottom, front, right-side perspective view of the holster device of FIG. 41.

FIG. 47 is a top, rear, right-side perspective view of the holster device of FIG. 41.

FIG. 48 is a bottom, front, left-side perspective view of the holster device of FIG. 41.

FIG. 49 is a front elevation view of the holster device of FIG. 41.

FIG. 50 is a rear elevation view of the holster device of FIG. 41.

FIG. 51 is a right-side elevation view of the holster device of FIG. 41.

FIG. 52 is a left-side elevation view of the holster device of FIG. 41.

FIG. 53 is a top view of the holster device of FIG. 41.

FIG. 54 is a bottom view of the holster device of FIG. 41.

FIG. 55 is a top, front, right-side perspective view of the holster device of FIG. 41.

FIG. 56 is a top, rear, left-side perspective view of the holster device of FIG. 41.

FIG. 57 is a top, front, left-side perspective view of the holster device of FIG. 41.

FIG. 58 is a top, rear, right-side perspective view of the holster device of FIG. 41.

FIG. 59 is a bottom, rear, right-side perspective view of the holster device of FIG. 41.

FIG. 60 is a bottom, rear, left-side perspective view of the holster device of FIG. 41.

FIG. 61 is a bottom, front, left-side perspective view of the holster device of FIG. 41; and,

FIG. 62 is a bottom, front, right-side perspective view of the holster device of FIG. 41.

The broken lines immediately adjacent to the shaded areas represent unclaimed boundaries of the ornamental design for the holster device.

The broken lines showing the remainder of the holster device are for environmental purposes only and form no part of the claimed design.

While the figures presently include some broken lines, I do contemplate a broader scope of invention and changing any of the present solid lines to broken lines wherein the broken lines are for the purpose of illustrating portions of the holster device and form no part of the claimed design.

Additionally, I do contemplate a scope of invention where any of the present broken lines are changed to solid lines.
